NUT-CRACKING MACHINE.

1,380,023.

Specification of Letters Patent.

Patented May 31, 1921.

Application filed March 6, 1920. Serial No. 363,772.

To all whom it may concern:

Be it known that I, PHILIPPE ROUSSILLON, citizen of the Republic of France, residing at Argenteuil, Seine and Oise, in the 5 Republic of France, have invented new and useful Improvements in Nut-Cracking Machines, of which the following is a specification.

This invention has for its object to provide 10 an improved machine for breaking the shells of hard-shelled fruits such as palm nuts, that is to say, breaking the shells without crushing the kernels. This improved machine has the advantage of dispensing with 15 all preliminary sorting of fruits of different sizes.

The improved machine comprises one or more pairs of crushing surfaces, each pair consisting of one of the faces of a rotary disk 20 revolving around a horizontal shaft, and a fixed wall. One or the other of these crushing surfaces is conical, so that the two surfaces form a conical space becoming gradually smaller toward the bottom, and in which 25 the nuts fall to a greater or less depth according to their size. One or other of the said surfaces has a helical portion which approaches gradually the other surface in such a manner that the shells of the nuts 30 are squeezed and finally broken between the said helical portion and the other surface. One of the surfaces, or both surfaces, is or are formed preferably with circular grooves for preventing the nuts from slipping and 35 moving away from the axis of rotation.

The accompanying drawings illustrate by way of example an improved machine constructed according to this invention. In these drawings:

40 Figure 1 is a vertical cross section of the improved crushing machine.

Fig. 2 is a diagrammatic longitudinal section thereof.

Fig. 3 is a plan thereof.

45 Fig. 4 is a longitudinal section of a pair of crushing surfaces.

Figs. 5 and 6 are respectively an elevation and a plan of a helical crushing surface.

In the example shown, the improved machine 50 comprises two disks 4 with conical surfaces, fixed on a horizontal shaft 3, arranged inside a rectangular casing 2 mounted on a bed-plate 1. The disks 4 are formed on their conical surfaces with radial ribs 14 designed to carry the fruits to be crushed 55

against helical surfaces 15, 16, 17, 18 (Fig. 5) formed on the vertical walls of the casing 2 which are at right angles to the shaft 3. Circular teeth or grooves 20, 20^a (Fig. 4) concentric to the shafts 3, are formed on 60 the helical surfaces and on the conical faces of the disks 4. These grooves are intended to prevent the nuts from slipping and moving away from the axis of rotation during the crushing. The fruits to be crushed fall 65 into the machine through a spout fed by a distributor not shown.

The improved machine is driven by means of pulleys 6 fixed on the end of a counter-shaft 13 supported in bearings 9 and 10. 70 The shaft 13 transmits its rotational motion to the shaft 3 through toothed wheels 7 and 8. The shaft 3 is carried in bearings 11 and 12. The last mentioned bearing is provided with a stop collar for taking the thrusts 75 due to the crushing.

The fruits to be crushed are poured into a hopper, and descend by means of the distributor and the spout 5 into the conical spaces formed between the conical faces of 80 the disks 4 and the vertical walls of the casing 2.

The improved machine as shown comprises four crushing compartments. In 85 each crushing group the fruits drop more or less closely to the center of the apparatus according to their size as shown at 19 (Fig. 5) for example, and the radial ribs 14 of the disk 4 carry them on to the portion of helical surfaces 15, 16, 17, 18 provided on the 90 vertical wall of the casing situated opposite the disk. The shell of each nut is thus squeezed, then broken by the approach of the generatrices of the conical disk toward those of the helical surface. The crushed 95 fruits fall through a hole provided for this purpose in the bed-plate.

It is to be understood that this invention is not limited to the constructional details described and shown, which are given solely 100 by way of example. For instance, cylindrical disks may be combined with conical helical surfaces for obtaining the same effects.

Having now described my invention, what 105 I claim as new and desire to secure by Letters Patent is;

1. A machine for breaking the shells of hard-shelled nuts comprising a fixed member and a rotatable member adapted to ro- 110

- tate about a horizontal axis, said members having opposite coöperating faces and being so arranged that the width of the cracking chamber left between said faces decreases progressively toward the said axis, a helical projection on the face of the fixed member, means for feeding nuts to the top of the periphery of said cracking chamber and means for rotating the rotatable member.
- 10 2. A machine for breaking the shells of hard-shelled nuts comprising a fixed member and a rotatable member adapted to rotate about a horizontal axis, said members having opposite coöperating faces and being so arranged that the width of the cracking chamber left between said faces decreases progressively toward the said axis, a helical projection on the face of the fixed member, means for feeding nuts to the top 15 of the periphery of said cracking chamber, circular teeth on the active faces of said members, radially arranged ribs on the rotatable member and means for rotating said member.
- 25 3. A machine for breaking the shells of hard shelled nuts comprising fixed members and a rotatable disk mounted in the space between said fixed members, the two opposite faces of which are adapted to coöperate 30 with the corresponding faces of the fixed members, respectively, said members being

so arranged that the width of the cracking chambers left between the coöperating faces decreases progressively toward the horizontal axis of the rotatable disk, a helical projection on the faces of said fixed members, means for feeding nuts to the top of the periphery of said cracking chambers and means for rotating the disk.

4. A machine for breaking the shells of hard shelled nuts comprising a plurality of fixed members, coaxial rotatable disks in the intervals between said fixed members, the two opposite faces of each disk being adapted to coöperate with the corresponding active faces of the fixed members and form a cracking chamber therewith, respectively, and the fixed member between the disks having active faces on both sides, said members being so arranged that the width of said cracking chambers decreases progressively toward the axis of the rotatable disks, a helical projection on one of the coöperating faces in each pair, means for feeding nuts to the top of the periphery of the cracking 55 chambers, a common shaft supporting the rotatable disks and means for rotating said shaft.

In testimony whereof I have signed my name to this specification.

PHILIPPE ROUSSILLON.
